POCKET PURSE

William G. Schaeffer, Rochester, N. Y.

Application July 24, 1933, Serial No. 681,922

1 Claim. (Cl. 150—28)

This invention relates to improvements in pocket purses and more particularly to a pocket container having a plurality of separate useful and handy compartments.

5 It is proposed in accordance with the present invention to provide a novel pocket purse suitable for holding money, license papers, calling cards and any other like articles, and to provide such a purse which is compact and still has easy 10 accessibility to the various compartments thereof. It is further proposed to provide a single opening and closing means for the two main compartments whereby a partial operation of the fastening means provides access to one compartment 15 containing the license papers, etc., and the full operation of the fastening means will provide access to the other compartment containing coins, etc. Still further, by attaching a single thickness of material the same shape as the purse 20 or preferably a billfold, to one of the sides of said purse, an open end compartment is formed which is found to be very useful for calling cards, etc.

The above various features of the invention 25 and the construction of the several compartments thereof will be more fully described as the description progresses, during which reference will be made to the accompanying drawing, in which:—

30 Fig. 1 is a perspective view of the back side of a pocket purse constructed in accordance with the present invention, showing the general shape of the purse with the top fastening means partially opened and showing a billfold attached 35 thereto.

Fig. 2 is an enlarged sectional view taken on the line 2—2 of Figs. 1 and 3, and viewed in the direction of the arrows, this view mainly showing the various compartments resulting from the 40 combination purse and billfold shown in Fig. 1.

Fig. 3 is a front perspective view of the article shown in the two previous views and more clearly shows the purse and the compartment therein and the complete opening and closing means 45 thereof.

Referring more particularly to Fig. 2 of the drawing, the main body of the purse is formed with two pieces of substantially rectangular shaped leather or other suitable flexible material 50 as 1 and 2, placed side by side, the bottom end of piece 1 being turned under and up to meet piece 2 and form a bottom for the purse, the two pieces forming a substantially U-shape when sewed together at the bottom where they meet.

55 A rectangular shaped partition piece 3 is then

inserted therebetween. The complete structure is then sewed together as follows:—First sew the three pieces together on the left-hand side (see Fig. 3), this procedure closing up the left side of the U-shaped main body. Next the partition piece 3 is sewed to piece 1 at the top and piece 2 at the bottom (see Fig. 2). This partition piece 3 is somewhat longer than pieces 1 and 2 and this extra length is bent backward and forward at the right-hand end against the main part of piece 3 to form a gusset as shown at 4 (see Fig. 3) and the extreme end is then also sewed to piece 2 at the right-hand end.

We now have a purse structure having two 15 separate compartments of substantially the same size, one compartment 5 having an end opening 6 and another compartment 7 having a top opening 8. A slide fastener or other suitable fastening means 9 having a slider 10, is then employed to close the right-hand end and the top 20 of the purse. It should be noted that a partial movement of the slider 10 up the right-hand end of the purse (slightly less than shown in Fig. 3) will expose opening 6 and allow entrance into compartment 5 without exposing opening 8 and 25 disturbing the contents of compartment 7. A further and complete movement across the top of the purse of the slider 10 will expose opening 8 and allow entrance to compartment 7 without 30 further exposing the contents of compartment 5. It is intended that compartment 5 will be used for license papers, etc., and compartment 7 will be used for coins, etc., although it should be understood that any other articles could be carried as the owner desires.

The above description pertains strictly to a 35 double compartment pocket purse and could be considered a unit in itself and used as such. However, as shown in the drawing, it is proposed to attach another unit 11 such as a billfold etc., 40 or a single rectangular shaped piece of leather to the pocket purse, this second unit 11 to be attached to the back piece 2 of the pocket purse unit by sewing or other suitable means at the bottom and both ends, thereby forming a compartment 12 between the two units which has an opening 13 at the top. This compartment 12 is 45 suitable for calling cards, etc., or for folded currency in case a single piece of leather is used in place of a billfold.

50 It should be noted at this time that no attempt will be made to claim a combination pocket purse and billfold as it is understood that this art is old.

55 It is believed that the above description is sufficient to point out the various features of this in-

vention and make it clear to be understood, and it is desired to be understood that various modifications, adaptations and alterations may be made therein without departing from the spirit or scope 5 of the present invention, except as limited by the appended claim.

Having thus shown and described my invention, what I claim is:—

10 A pocket purse comprising a rectangular shaped main body portion of flexible material substantially U-shaped in cross section and closed in at one end, a partition piece of flexible ma-

terial inserted within said body portion and fastened therein in such a way as to form two substantially equal sized compartments each including but one side of the U-shaped body portion and each with a single opening, with the openings facing at approximately 90 degrees to each other, a single interlocking fastening means attached to the two open sides of the structure and operable to completely close the openings of said two compartments. 5

WILLIAM G. SCHAEFFER.
